Primary Examiner — Dana K Weiland*Assistant Examiner* — Emily Anna Saunders(74) Attorney, Agent, or Firm — Fitzgerald IP Law; John K Fitzgerald, Esq.(57) CLAIM

The ornamental design for a toy car, as shown and described.

DESCRIPTION

FIG. 1 is a perspective view of the front, top, and left side of a toy car showing my new design;

FIG. 2 is a perspective view of the rear, top, and right side thereof;

FIG. 3 is a front side view thereof;

FIG. 4 is a rear view thereof;

FIG. 5 is a top plan view thereof;

FIG. 6 is a right side view thereof;

FIG. 7 is a left side view thereof; and,

FIG. 8 is a perspective view of the front, top, and left side, showing the top of the toy car being removed and in a position of use to allow access to an interior of the top of the toy car.

The broken lines shown are included for the purpose of illustrating portions of the article which form no part of the claimed design.

1 Claim, 8 Drawing Sheets(56)
